HENRY PERAZZOLI, OF PHILADELPHIA, PENNSYLVANIA

TROLLEY WIRE CONTACT HOOK

Application filed April 4, 1929. Serial No. 352,567.

The present invention relates to an improved contact hook and pole particularly adapted for engaging trolley wires, the purpose of the invention being to provide a device, so engaging with the trolley wire as to permit current to be carried from the trolley wire to a grinding machine or any other machine when repairing tracks.

In devising a contact hook and pole it is a further purpose to provide a construction such as will permit the contact hook to remain in engagement with the trolley wire while cars are passed, and without either disengaging the hook or disengaging the trolley wheel.

Still another purpose is to provide a contact hook comprising opposed jaws, which are actuated by gravity, due to the weight of the pole to insure a constant contact with the wire, the construction and arrangement of the two jaws being such that when the pole is lifted, or gravity relieved the jaws will automatically open and hence permit the hook to be detached from the wire.

Another feature of the invention is the provision of a combined rest and guide, whereby one of the jaws may be supported on the rest and in such a manner that when the contact hook is in the act of engaging a trolley wire, say for instance the initial act, the rest will act to guide the trolley wire into engagement with the upper jaw, so that when gravity is exercised the lower jaw will clamp under the trolley wire.

It is to be understood that the particulars herein given are in no way limitative, and that while still keeping within the scope of the invention, any desired modification of details and proportions may be made in the construction of the appliance according to circumstances.

The invention comprises further features and combination of parts to be hereinafter set forth, shown in the drawings and claimed.

In the drawings:

Figure 1 is a view in elevation showing the jaws open, the lower jaw engaging a combined rest and guide, and illustrating several sections of the pole to render the hook pole extensible.

Figure 2 is a view in elevation at right angles to that in Figure 1, showing the jaws open and in the act of engaging a trolley wire, which is being guided into engagement with the upper jaw, a portion of the movable jaw also acting as a guide to accomplish this result.

Figure 3 is a view in elevation showing the two jaws closed in engagement with the trolley wire.

Figure 4 is a plan view.

Referring to the drawings, 1 identifies a metal tubular pole having a sleeve 2 at one end and a head 3 at the upper end, the head being threaded at 4 and pinned at 5 to the tubular pole. The head has an arm 6 pivoted therein at 7. The head is also provided with a guide opening 8, and projecting from the head is a curved flange 9 constituting a rest and guide.

A forked member 10 is provided, the two forks 11 extend upwardly and curve over toward and down to one side and in parallelism, as shown in the plan view.

These forks terminate in an integral elongated jaw 12, which is semi-circular or curved in cross section. This jaw is adapted to engage with the upper cylindrical surface of a trolley wire 13, the upper cylindrical surface is usually corroded or otherwise scaled, therefore the upper jaw does not insure a perfect contact. However the lower surface of the trolley wire is kept smooth and highly polished due to the trolley wheel engaging therewith.

Pivoted between the forks at 14 is a lever 15, comprising a curved arm 17 and a straight arm 16, which in turn is pivoted to the arm 6. This curved arm extends laterally and downwardly and terminates in a contacting lower jaw 18. The lower jaw 18 is curved in cross section and makes a perfect contact with the lower polished surface of the trolley wire. Between the jaw 18 and the pivot of the lever the arm 17 is enlarged. The enlargement 19 is of a triangular contour, and its edge 20 is curved constituting a cam.

When the pole is in the act of being raised to engage the hook with the trolley wire the

lower jaw engages between the combined rest and guide and the forked member. The pole is lifted high enough so that the trolley wire will engage the side of the pole, immediately adjacent the lower portion of the combined rest and guide. By lowering the pole, in fact allowing the gravity of the pole to take effect the wire will cam over the lower jaw, then cam against the curved edge of the enlargement 19 and finally in contact with the upper jaw, and then by permitting gravity to take effect entirely the lower jaw will automatically clamp against the lower cylindrical surface of the wire, and hence insure a contact.

A pair of wire cables 20a are soldered, brazed or otherwise connected securely to the head, and in turn similarly connected at 21 to the lever immediately adjacent the triangular enlargement.

The tubular pole section 1 is constructed of suitable current conducting metal, and fastened by a clamp 22 to the lower portion of this pole section is a conducting wire 23, which may be insulated and may terminate in a plug not shown for plugging in on a grinding or other kind of machine for repairing tracks.

The sleeve 2 may thread into a sleeve 24 of a wooden pole section 25, which in turn has a threaded sleeve 26 at its other end which may thread to a second wood pole section 27, rendering the pole for the hook extensible. In order to provide for increased length a third pole section 29 may connect with the sleeve 28 of the second pole section, so that the contact hook may be held substantially to one side of a passing car.

It is to be noted that the lower clamp of the hook is curved longitudinally to permit the groove of the trolley wheel to pass thereover, without the necessity of disengaging the hook from the wire.

The invention having been set forth, what is claimed is:

1. In a contact hook for trolley wires, the combination with a slideable member having an upper trolley wire engaging jaw, of a trolley pole having a guiding head for the slideable member, a lever pivoted upon the slideable member and having a lower trolley wire engaging jaw, a link connecting the lever and said guiding head whereby as the head gravitates the lever will tilt and cause the lower jaw to engage the trolley wire and clamp the same between the two jaws.

2. In a contact hook for trolley wires, the combination with a slideable member having an upper trolley wire engaging jaw, of a trolley pole having a guiding head for the slideable member, a lever pivoted upon the slideable member and having a lower trolley wire engaging jaw, a link connecting the lever and said guiding head whereby as the head gravitates the lever will tilt and cause

the lower jaw to engage the trolley wire and clamp the same between the two jaws, the guiding head having a combined rest and guide, between which and the lower end of the slideable member the lower jaw may engage, a cam on the lever in alignment with the lower jaw when lowered and partially in alignment with the guide and rest for guiding the trolley wire in engagement with the upper jaw.

3. In a contact trolley hook, a trolley pole having a guiding head, a slideable member mounted operatively in the guiding head and having an upper trolley wire engaging jaw, a lever pivoted on the slideable member, a lower trolley wire engaging jaw carried by one end of the lever, a link connecting the other end of the lever and the head, a combined rest and guide carried by the guiding head between which and the slideable member the lower jaw may engage.

4. In a contact trolley hook, a trolley pole having a guiding head, a slideable member mounted operatively in the guiding head and having an upper trolley wire engaging jaw, a lever pivoted on the slideable member, a lower trolley wire engaging jaw carried by one end of the lever, a link connecting the other end of the lever and the head, a combined rest and guide carried by the guiding head between which and the slideable member the lower jaw may engage, the lower jaw being shaped to guide the trolley wire into engagement with the upper jaw, and means connecting one end of the lever and the guiding head to actuate the lower jaw in engagement with the trolley wire when the guiding head and pole gravitate.

5. The combination with a tubular body member, having a head at its upper end, said head being apertured off center, a guide rod slidably disposed in said aperture and body member, an upper jaw having a pair of similarly curved arms merging into and forming a part of said guide rod, a supporting link pivoted in the side of said body member, a lower jaw having its lower edge substantially convex, a curved arm for said lower jaw pivotally connected to the free end of said supporting link, the curved arm of said lower jaw being also pivoted between the similarly curved arms of the upper jaw, and cable conductors secured to and leading from the curved arm into the tubular body member.

6. A trolley contact hook, comprising a pole having a head, a forked member having a stem guided in the head, the forks of the member terminating in an overhanging wire engaging jaw, a link pivoted to the head, a lever between the forks of the forked member, with one end pivotally connected to the link, the other end of the lever terminating in a second trolley wire engaging jaw to oppose the first jaw, the second jaw disengaging from the wire upon lifting the pole.

7. A trolley contact hook, comprising a

6 pole having a head, a forked member having
a stem guided in the head, the forks of the
member terminating in an overhanging wire
engaging jaw, a link pivoted to the head, a
lever pivoted between the forks of the forked
member with one end pivoted to the link, the
other end of the lever terminating in a second
trolley wire engaging jaw to oppose the first
jaw, the second jaw disengaging from the
10 wire upon lifting the pole, a combined rest
and guide projecting from the head, and be-
tween which and the lower end of the forked
member the lower jaw may engage when the
forked member is lowered, said lever having
15 a guiding cam substantially in alignment
with the combined rest and guide, whereby
a trolley wire may be guided or cammed in
engagement with the upper jaw, and whereby
when the head gravitates, the two jaws will
20 close in engagement with the wire.

25 In testimony whereof he affixes his signature.

HENRY PERAZZOLI.
